UNITED STATES PATENT OFFICE

GEORGE U. MEYER, OF RIVERVIEW, RHODE ISLAND, ASSIGNOR TO PROVIDENCE STOCK COMPANY, A CORPORATION OF RHODE ISLAND

DESIGN FOR A BRACELET CHAIN

Application filed March 19, 1931. Serial No. 39,150. Term of patent 3½ years.

To all whom it may concern:

Be it known that I, GEORGE U. MEYER, a citizen of the United States, residing in Riverview, county of Kent, and State of Rhode Island, have invented a new, original, and ornamental Design for a Bracelet Chain, of which the following is a specification, reference being had to the accompanying drawings forming a part thereof.

Fig. 1 is a plan view of a bracelet chain showing my new design; Fig. 2 is a side elevation and Fig. 3 is a section on the line 3—3 of Fig. 1, of the same.

I claim:

The ornamental design for a bracelet chain, substantially as shown.

GEORGE U. MEYER.
